[57] CLAIM

The ornamental design for telephone handset hang-up holder or similar article, as shown and described.

DESCRIPTION

FIG. 1 is a bottom, front, and right side perspective view of a telephone handset hang-up holder or similar article showing our new design in full lines, with the broken line matter being for illustrative purposes only and forming no part of the claimed design;

FIG. 2 is a left side elevational view thereof;

FIG. 3 is a bottom plan view thereof; and

FIG. 4 is a rear elevational view thereof.
